ELECTRIC ALARM CLOCK

William K. Sessions, Jr., Bristol, and Earl D. Brightman, Forestville, Conn., assignors to The Sessions Clock Co., Forestville, Conn., a corporation of Connecticut

Application November 26, 1947, Serial No. 788,292

22 Claims. (Cl. 58—38)

1

The present invention relates in general to timepieces and more especially to the alarm mechanism of an electric alarm clock.

An object of the invention is to provide a superior alarm mechanism for electric alarm clocks.

A further object of the invention is to provide an electric alarm clock with superior alarm mechanism wherein the component parts thereof are relatively few in number and adapted to be assembled wholly within the confines of the alarm-bell.

A still further object of the invention is to provide improved alarm mechanism embodying a bell in which all of the elements of the alarm mechanism are mounted and which constitutes one of the movement-plates of the timepiece.

A still further object of the invention is to provide superior mechanical alarm-means which is dependable in operation, secured against inadvertent disarrangement and adapted to give a resonant unmuffled bell tone.

With the above and other objects in view, as will appear to those skilled in the art from the present disclosure, this invention includes all features in the said disclosure which are within the scope of the appended claims.

In the accompanying drawings, in which certain modes of carrying out the present invention are shown for illustrative purposes:

Fig. 1 is a front elevation of an electric alarm clock embodying the present invention;

Fig. 2 is an enlarged side elevation of the timepiece shown in Fig. 1;

Fig. 3 is a rear elevation of the timepiece showing the alarm mechanism and electric motor mounted in the bell;

Fig. 4 is a side elevation partly in section of the bell and alarm mechanism shown in Fig. 3;

Fig. 5 is a rear elevation of the timepiece similar to Fig. 3, except that the actuating-member of the alarm mechanism has been disconnected from the eccentric-pin of the motor by the alarm-shutoff lever;

Fig. 6 is a perspective view of the rotor of the electric motor, including the eccentric-pin;

Fig. 7 is a perspective view of one of the lever-members of the toggle-joint;

Fig. 8 is a perspective view of the second lever-member of the toggle-joint, including an integral bell-hammer;

Fig. 9 is a perspective view of the actuating-link for connecting the eccentric-pin to the toggle-joint; and

Fig. 10 is a perspective view of the manually-

2

operated alarm-shutoff lever and its guard-finger.

The particular electric alarm clock described and disclosed herein as an exemplary embodiment of the invention includes a dial 15, the usual minute-hand and hour-hand 16 and 17 respectively, and a seconds pointer 18, all of which are arranged to be driven about the dial 15 by the propelling-unit and time-train assembly described in detail in the patent of Raymond E. Hutchinson, No. 2,211,426, dated August 13, 1940.

The dial 15 is carried on the front face of a dial back-plate 19 (see Fig. 2) which is preferably a substantially-flat disk-shaped metal-member provided with a central opening for the passage of the mounting and operating means of the hands 16 and 17 and the seconds pointer 18. The aforementioned time-train is indicated generally at 20 and inasmuch as the specific details of this mechanism are not essential to a full and clear disclosure of the present invention, a more detailed description thereof is omitted. It will suffice, therefore, to point out that the time-train 20 is adapted to be driven by a propelling-unit, indicated generally at 21, which is a self-starting synchronous electric motor having a worm 22 projecting from its front face arranged as described more fully in the aforementioned patent, to drive the time-train 20.

30 The time-train 20 and the electric motor 21 are supported by a movement-frame which constitutes the dial back-plate 19 and the substantially-flat disk-shaped bottom wall or bell-head 23 of a cup-shaped alarm-bell indicated generally at 24, the alarm-bell being supported on the back of the dial back-plate by means of three suitably-spaced pillars 25 which support the dial back-plate and the head 23 of the bell in spaced parallel relationship with the cylindrical side wall 26 of the bell 24 extending rearwardly at substantially right angles to the bell-head 23. It will be clear that the dial back-plate 19 thus constitutes both the dial back-plate of the timepiece and the front movement-plate and that the bell-head 23 constitutes the rear movement-plate of the timepiece.

For the purposes of the present invention, the electric motor 21 need be but briefly described. Electric current from a suitable source may be supplied to leads 27 which pass through openings provided in a stator 28. Preferably, certain of the salient-poles of the stator are shaded by suitably-pierced shading-rings 31 formed of copper or the like which are permanently organized 50 with the stator 28 to produce a rotating field

effect and secure a self-starting synchronous motor structure.

Arranged to be acted on by the rotating field of the motor is a rotor 32 (see Fig. 6) having a forwardly-extending flange 33 which overlies and turns about the inter-fitted salient-poles of the stator. The rotor 32 is rigidly secured to a collet 34 and the collet, in turn, is rigidly secured to the rear end of a rotor-shaft 35. The collet 34 which is rotatable with the rotor 32 extends rearwardly therefrom, as shown clearly in Fig. 4, and is provided with an eccentric-pin 36 which projects rearwardly of the rotor 32, for the purpose hereinafter described. The rotor-shaft 35 extends forwardly of the rotor 32 and projects through an aperture in the head 23 of the alarm-bell to provide a forwardly-extending stem on which the worm 22 is secured. The electric motor 21 is fixedly mounted on the rear face of the bell-head 23 of the movement-frame within the confines of the side wall 26 by suitable means such as studs 37 which project from the forward end of the cup-shaped pole-piece 28 through the bell-head 23.

The alarm mechanism is indicated generally at 38 and as especially well shown in Figs. 3, 4 and 5, is supported by the bell-head 23 within the confines of its side wall 26 and in juxtaposition to the electric motor 21. The alarm mechanism 38 constitutes mechanical alarm-means which is adapted to actuate a hammer for striking the wall 26 of the alarm-bell and is supported as a unit within the side wall 26 by means of a mounting-plate 39 which, as indicated in Figs. 3 and 5, is a flat substantially-U-shaped plate riveted or otherwise secured to the rear face of the bell-head 23 with its U-shaped opening facing outwardly radially and immediately over an aperture 40 of the bell-head 23. The aperture 40 constitutes guide-means for the automatic alarm-setting-and-releasing shaft 41 of the timepiece which, as shown in Fig. 4, is provided at its rear end with a head 42 adapted normally to be held in its rearmost position in the bell so as to disconnect the alarm mechanism of the timepiece, as hereinafter described; and in its forward position to release the alarm mechanism so as to permit the alarm mechanism to be connected with the propelling-unit, the forward and rearward movements of the shaft 41 being controlled automatically by an alarm time-train described more fully in the aforementioned patent.

Extending rearwardly substantially perpendicularly from the mounting-plate 39 are three pivot-posts 43, 44 and 45, each of which is provided with an axial aperture in its upper end to receive a pin or similar fastening-means for pivotally securing an element of the alarm mechanism thereto, as hereinafter described.

Referring especially to Figs. 7, 8, 9 and 10, the alarm mechanism comprises a toggle-joint indicated generally at 46 and characterized by a loosely-jointed knee 47. The toggle-joint 46 consists of a lever 48 having an aperture 49 at its rear end and tapering forwardly so as to terminate at its forward end in a relatively-narrow tang 50 bent rearwardly at substantially right angles thereto. Formed in the lever 48 intermediate its apertured rear end and its tang 50, is an aperture 51.

The second lever of the toggle-joint comprises the member 52 having an aperture 53 at one end and a slot 54 at its opposite end extending substantially longitudinally thereof. The slot 54 is preferably closed at both ends, but it may inter-

sect the outer free end of the lever 52. Formed integrally with the latter and at the apertured end thereof, is a hammer comprising a hammer-arm 55 having an enlargement or hammer-head 56 at the outer free end thereof, the arm 55 making an angle of substantially 119° with the lever 52 and being bent forwardly from the vertical plane thereof so as to locate the hammer-head 56 in a substantially-vertical plane intermediate the forward and rearward edges of the side wall 26, as indicated clearly in Fig. 4, and normally immediately adjacent the cylindrical inside surface thereof.

The lever 48 of the toggle-joint is adapted to be mounted on the top of the post 43 and to be pivotally secured thereto by a flanged pivot-pin 57 arranged to make a press fit in the axial aperture of the post 43. The lever-member 52 of the toggle-joint is similarly secured to the top of the post 45 by a flanged pivot-pin 58, the slotted end of the lever 52 being engaged over the tapered free end of the lever 48 with the tang 50 of the lever 48 projecting up through the slot 54. As shown clearly in Figs. 3 and 5, the width of the tang 50 is less than the width of the slot 54 so that the tang has appreciable free or lost motion transversely of the slot. The length of each toggle-joint post 43 and 45 is such that the toggle-joint 46 is supported substantially in the vertical plane of the rear edge of the side wall, as indicated in Fig. 4.

Loosely connected to the lever 48 of the toggle-joint at its aperture 51 by a third flanged pin 59 or similar fastening-means, is the apertured end 60 of an actuating-member or link 61, the opposite end of which is provided with an asymmetrical enlargement 62 having a straight bottom edge 63 which constitutes a continuation of the bottom edge 64 of the link 61. The enlargement 62 is provided with a substantially-U-shaped notch 65 which intersects its bottom edge 63, and which has right and left walls spaced apart a distance slightly greater than the diameter of the eccentric-pin 36, as shown and for the purpose hereinafter described. For optimum performance, the lower outer corners of the notch 65 are rounded off as indicated at 66. Adjacent the opposite end of the link 61 is a link-disconnecting cam-plate 67 which, as shown in Fig. 9, is integral or otherwise secured at its upper end to the bottom edge 64 of the link 61 and at substantially right angles thereto, the lower end 68 of the cam-plate 67 being bent upwardly and forwardly for engagement by the head 42 of the alarm-setting shaft 41, in the manner described below.

The normal position of the actuating-link 61 is its inoperative position, as indicated in Fig. 5, wherein the link is swung upwardly so as to disengage its notch 65 from the eccentric-pin 36 of the rotor, thereby to interrupt the transmission of motion to the bell-hammer 56 and the consequent ringing of the bell. This normal inoperative position of the actuating-link 61 may be effected either automatically or manually.

Referring especially to Fig. 10, the manual means for throwing the actuating-link upwardly into its inoperative position comprises an alarm-shutoff lever 69 which is provided with an aperture 70 intermediate its opposite ends for fastening-means 71 arranged to pivotally secure the alarm-shutoff lever 69 to the top of the post 44, the fastening-means 71 being adapted to frictionally engage the top of the lever 69 so as to hold the latter in any set position. The outer end of the lever 69 comprises a reach 72 which is offset

rearwardly from the plane of the lever and provided with a finger-piece 73 at its outer end, bent or otherwise formed substantially perpendicular thereto and adapted to extend rearwardly through an arcuate guide-slot 74 in the back-plate 75 of the timepiece, as indicated clearly in Figs. 3 and 5, for manipulating the alarm-shutoff lever. The opposite end of the alarm-shutoff lever 69 comprises a bifurcated reach 76, the longitudinal axis of which is substantially in alignment with the reach 72, the furcation 77 of the reach 76 being provided at its outer end with a lifting-finger 78, bent or otherwise formed at substantially right angles thereto and forwardly thereof. The furcation 79 of the reach 74 embodies a guard-finger 80 which extends beyond the lifting-finger 78 and is adapted to overlie the actuating-link 61 when the latter is in either its normal inoperative position or its operative position, in order to retain the link and in particular its notch 65 in operative relationship with the eccentric-pin 36, that is to say, to prevent the enlarged end 62 of the actuating-link from being sprung rearwardly so as to overlie the eccentric-pin.

The manipulation of the alarm-shutoff lever 69 to engage and disengage the actuating-link 61 is indicated in Figs. 3 and 5, the normal position of the alarm-shutoff lever being shown in the latter figure wherein the lifting-finger 78 of the lever has engaged the bottom edge 64 of the actuating-link and lifted its notch 65 out of engagement with the eccentric-pin of the rotor so as to disconnect the toggle-joint and hammer of the alarm-bell, the finger-piece 73 of the alarm-shutoff lever being at the bottom of the slot 74 in the back-plate of the timepiece. When the alarm-shutoff lever is swung in a clockwise direction so as to bring the finger-piece 73 to the upper end of the slot 74, the lifting-finger 78 is withdrawn from engagement with the bottom edge 64 of the actuating-link, as indicated clearly in Fig. 3, thereby permitting the latter to swing downwardly or clockwise into its operative position wherein its notch 65 engages the eccentric-pin 36 of the rotor 32.

The actuating-link 61 is also adapted to be moved into its inoperative and operative positions respectively by means of the aforementioned automatic alarm-setting shaft 41 wherein the head 42 thereof is arranged normally to extend rearwardly into the bell in engagement with the cam-plate 67 of the actuating-link to hold the notch 65 of the latter up out of engagement with the eccentric-pin of the rotor; and on its forward movement, which is accomplished automatically by the alarm-setting mechanism, to disengage the cam-plate and permit the actuating-link to drop back into operative engagement with the eccentric-pin.

In order to facilitate re-engagement of the notch 65 of the actuating-link with the eccentric-pin for any position of the latter, the width of the notch 65 is made somewhat greater than the diameter of the eccentric-pin and its corners 66 rounded so that when the notched edge 63 of the actuating-link drops down onto the eccentric-pin, the latter will readily engage the notch. Normally, the weight of the hammer tends to hold the knee 47 of the toggle-joint downwardly, as seen in Fig. 5, and hence to displace the notch 65 of the actuating-link to the extreme right of the locus of the eccentric-pin. Under these conditions, if the actuating-link is released at a time when the pin is to the left of the notch 65, the inner portion 630 of the notched bottom edge 63

of the link will fall onto the eccentric-pin and as the latter moves downwardly and away therefrom, it will ride along the inner portion 630 until it arrives opposite the notch 65, whereupon the pin enters therein. If, on the other hand, the actuating-link is released at a time when the eccentric-pin is to its extreme right, the rounded outer corner 66 of the notch 65 will engage the pin and as the latter moves upwardly and away from the rounded corner 66, it enters the notch 65. In this connection it should be pointed out since the actuating-link is at the extreme right end of its reciprocable movement and is thus positively prevented from further movement in this direction by engagement of the hammer with the side wall of the bell, it is imperative that the outer corner 66 be accurately located with respect to the eccentric-pin so as to prevent a jam. To this end, it has been found that when the outer portion 631 of the notched bottom edge 63 of the link is substantially in alignment with the inner portion 630, the required height of the right and left walls of the U-shaped notch 65 may be maintained and the outer corner 66 of the notch located in an optimum position with respect to the pin for facilitating entry thereof into the notch.

In its operating position, the notch 65 of the actuating-link 61 engages the eccentric-pin 36 which imparts a compound reciprocating and oscillating motion to the link 61 for actuating the toggle-joint 43 and causing the hammer to strike and to be positively withdrawn from the side wall 26. In this connection, it should be pointed out that when the tang 50 of the toggle-joint has been pulled down to its lowermost position by the actuating-link 61, as indicated by the broken lines in Fig. 3, the hammer-head is in engagement with the side wall, but the edges of the slot 54 of its lever 52 are clear of the corresponding sides of the tang. Consequently, the hammer-head is permitted to rebound freely after striking the side wall 26, thus insuring a clear unmuffled resonant bell tone. As the tang is moved upwardly clockwise, it picks up the hammer-lever 52 and positively swings the hammer-head upwardly away from the side wall. At the upper limit of its movement, the tang 50 reverses its direction of movement, thereby imparting a sudden kick to the hammer-lever 52 whereby the hammer-head is impelled forcefully but substantially unrestrainedly against the side wall 26 to give a clear bell tone.

The operation of the alarm mechanism may be described briefly as follows. Assuming the shutoff-lever 69 is in its operative position, as shown in Fig. 5, thereby disengaging the actuating-link 61 from the eccentric-pin of the rotor and that current from a suitable source is entering the motor by way of the leads 27, then the rotor 32 and its eccentric-pin 36 will rotate in a counter-clockwise direction, as indicated by the arrow in Figs. 3 and 5, and the alarm-hammer will remain immobile. To actuate the alarm-hammer, the manually-operated shutoff-lever is swung downwardly in a clockwise direction to its position shown in Fig. 3 thereby releasing the actuating-link 61 so as to permit its notch 65 to engage the eccentric-pin of the rotor. In consequence thereof, the toggle-joint 43 is actuated, thereby imparting bell-striking motion to the hammer 56, the alarm being sounded as long as the actuating-link remains in engagement with the eccentric-pin. The alarm may be shut off manually by swinging the lever 69 upwardly so as to engage its finger 78 with the bottom edge 64 of the link and

lift its notch 65 out of engagement with the eccentric-pin 36.

Similar movements of the actuating-link 64 to and from its alarm-operating position may be effected automatically by the alarm-setting mechanism of the timepiece (not shown) which is arranged to set the head 42 of the alarm-setting shaft 41 in engagement with the cam-plate 67 of the actuating-link so as to hold the latter upwardly in its inoperative position until such time as the alarm-setting mechanism automatically releases the alarm-setting shaft 41 so as to permit its head 42 to move forwardly automatically out of engagement with the cam-plate 67 of the actuating-link, thereby to permit the notch 65 of the latter to re-engage the eccentric-pin and actuate the alarm.

As will be apparent, the construction and arrangement of the parts herein shown and described are such as to secure the carrying out of the operations above set forth in a superior and effective manner by mounting the alarm mechanism, including the electric motor, in the bell of the alarm, the respective parts being compactly arranged and yet the relationship of the parts is such that the desired compactness is secured without cramping. Moreover, by using an alarm-bell both as a supporting-means for the alarm mechanism and motor of the timepiece as well as the one element of the movement-frame, a timepiece is provided which is relatively inexpensive and comprises relatively few easily assembled elements.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. In an electric alarm clock: a cup-shaped bell comprising a bottom wall and a side wall; an electric motor mounted on said bottom wall within said side wall, said electric motor having a continuously-rotatable eccentric hammer-actuating pin; and mechanical alarm-means mounted on said bottom wall in juxtaposition to said motor, comprising a toggle-joint, a hammer operatively connected to one end of said toggle-joint and an actuating-member engaged at one end by said eccentric-pin and pivoted at its opposite end to the opposite end of said toggle-joint thereby to transmit the movement of said actuating-member to said hammer for striking the side wall of said bell.

2. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint, a hammer formed integrally at one end of said toggle-joint and an actuating-member engaged at one end by said eccentric-pin and pivoted at its opposite end to the opposite end of said toggle-joint thereby to transmit the movement of said actuating-member to said hammer for striking the side wall of said bell.

3. In an electric alarm clock: a cup-shaped bell comprising a bottom wall and a side wall;

an electric motor mounted on said bottom wall within said side wall, said electric motor having a continuously-rotatable eccentric hammer-actuating eccentric-pin within said bell; and mechanical alarm-means mounted on said bottom wall in juxtaposition to said motor, comprising a toggle-joint, a hammer formed integrally at one end of said toggle-joint, an actuating-member having a recess at one end arranged to operatively engage said eccentric-pin and a pivotal member arranged to connect the opposite end of said actuating-member to the opposite end of said toggle-joint thereby to transmit the movement of said actuating-member to said hammer for striking the side wall of said bell.

4. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint, a hammer formed integrally at one end of said toggle-joint, an actuating-member having an enlargement at one end provided with a notch in one edge thereof arranged to operatively engage said eccentric-pin and a pivotal member arranged to connect the opposite end of said actuating-member to the opposite end of said toggle-joint thereby to transmit the movement of said actuating-member to said hammer for striking the side wall of said bell.

5. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint, a hammer formed integrally at one end of said toggle-joint, an actuating-member comprising an arm having an asymmetrical enlargement at one end, one edge of said enlargement being an extension of one edge of said arm and intersected by a substantially-U-shaped notch arranged to operatively engage said eccentric-pin and a pivot-pin arranged to connect the opposite end of said actuating-arm to the opposite end of said toggle-joint thereby to transmit the movement of said actuating-arm to said hammer for striking the side wall of said bell.

6. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint, a hammer formed integrally at one end of said toggle-joint, an actuating-member comprising an arm having an asymmetrical enlargement at one end, one edge of said enlargement being an extension of one edge of said arm and a U-shaped notch intersecting the said one edge of said asymmetrical enlargement, said U-shaped notch exceeding in width the diameter of said eccentric-pin whereby said notch is arranged to operatively engage said eccentric-pin with a relatively-loose fit, and a pivot-pin arranged to connect the opposite end of said actuating-arm to the opposite end of said toggle-joint thereby to transmit the movement of said actuating-arm to said

hammer for striking the side wall of said bell. 7. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint, a hammer formed integrally at one end of said toggle-joint, an actuating-member having a notch at one end arranged to operatively engage said eccentric-pin, and a pivot-pin arranged to connect the opposite end of said actuating-member to the opposite end of said toggle-joint thereby to transmit the movement of said actuating-member to said hammer for striking the side wall of said bell; and an alarm-shutoff lever mounted without said side wall and arranged to engage said actuating-member to lift its notch from said eccentric-pin so as to disengage the latter from said toggle-joint and discontinue the bell-striking operation of said hammer.

8. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint, a hammer formed integrally at one end of said toggle-joint, an actuating-member having a notch at one end arranged to operatively engage said eccentric-pin, and a pivot-pin arranged to connect the opposite end of said actuating-member to the opposite end of said toggle-joint thereby to transmit the movement of said actuating-member to said hammer for striking the side wall of said bell; an alarm-shutoff lever having a finger-grip at one end thereof; and a pivotal-member arranged to support said lever intermediate its ends without said side wall, the opposite end of said lever being arranged to be swung into engagement with said actuating-member by manipulation of said finger-grip to lift the notch of said member from said eccentric-pin so as to disengage the latter from said toggle-joint and discontinue the bell-striking operation of said hammer.

9. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint, a hammer formed integrally at one end of said toggle-joint, an actuating-member having a notch at one end arranged to operatively engage said eccentric-pin, and a pivot-pin arranged to connect the opposite end of said actuating member to the opposite end of said toggle-joint thereby to transmit the movement of said actuating-member to said hammer for striking the side wall of said bell; an alarm-shutoff lever mounted without said side wall and arranged to engage said actuating-member to lift its notch from said eccentric-pin so as to disengage the latter from said toggle-joint and discontinue the bell-striking operation of said hammer; and a guard carried by said alarm-shutoff lever arranged to extend over said actuating-member in both its operative and inoperative positions to retain said actuating-

member with the range of operation of said eccentric-pin.

10. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint, a hammer formed integrally at one end of said toggle-joint, an actuating-member having a notch at one end arranged to operatively engage said eccentric-pin, and a pivot-pin arranged to connect the opposite end of said actuating-member to the opposite end of said toggle-joint thereby to transmit the movement of said actuating-member to said hammer for striking the side wall of said bell; an alarm-shutoff lever having a finger-grip at one end thereof; a pivotal-member arranged to support said lever intermediate its ends without said side wall, the opposite end of said lever being arranged to be swung into engagement with said actuating-member by manipulation of said finger-grip to lift the notch of said member from said eccentric-pin so as to disengage the latter from said toggle-joint and discontinue the bell-striking operation of said hammer; and an integral guard-finger projecting forwardly from the opposite end of said alarm-shutoff lever to extend over the actuating-member in both its operative and inoperative positions to retain the latter within the range of operation of said eccentric-pin.
11. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint characterized by a loosely-jointed knee, a hammer formed integrally at one end of said toggle-joint and an actuating-member engaged at one end by said eccentric-pin and pivoted at its opposite end to the opposite end of said loosely-jointed toggle thereby to transmit the movement of said actuating-member to said hammer for impelling the latter against the side wall of said bell, the said loosely-jointed knee of said toggle-joint being arranged to allow said hammer to rebound freely from said side wall after each stroke so as to enhance the resonance of the bell tone.
12. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a hammer arranged to strike said side wall, an actuating-member driven by said eccentric-pin, and lever-mechanism arranged to interconnect said hammer and said actuating-member so as to transmit the movement of said actuating-member to said hammer for impelling the latter against the side wall of said bell, said lever-mechanism comprising a lever-arm pivotally supported at one end within said bell-wall, a tang at the opposite free end of said lever-arm, a fastening-member intermediate the opposite ends of said lever-arm to

pivots to connect said actuating-member thereto, and a bell-crank member pivotally supported intermediate its ends within said bell-wall, said bell-crank having the hammer at one end thereof arranged to strike said side wall and a slot at its opposite end arranged to receive said tang so as to operatively connect said lever-arm and said bell-crank.

13. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a hammer arranged to strike the side wall of said bell, an actuating-member driven by said eccentric-pin and lever-mechanism arranged to interconnect said hammer and said actuating-member so as to transmit the movement of said actuating-member to said hammer for impelling the latter against said side wall, said lever-mechanism comprising a lever-arm pivotally supported at one end within said side wall, a tang at the opposite free end of said lever-arm, a fastening-member intermediate the opposite ends of said lever-arm to pivotally connect said actuating-member thereto, and a bell-crank member pivotally supported intermediate its ends within said side wall, said bell-crank having the hammer at one end thereof arranged to strike said side wall and a slot at its opposite end arranged to receive said tang, said slot exceeding in width the corresponding dimension of said tang so as to provide a loose connection between said lever-arm and said bell-crank thereby to allow said hammer to rebound freely from said side wall after each stroke so as to enhance the resonance of the bell tone.

14. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint characterized by a loosely-jointed knee, a hammer formed integrally at one end of said toggle-joint and an actuating-member having an enlargement at one end provided with a notch in one edge thereof arranged to operatively engage said eccentric-pin, said actuating-member being pivotally connected at its opposite end to the opposite end of said toggle-joint thereby to transmit the movement of said actuating-member to said hammer for impelling the latter against the side wall of said bell, the said loosely-jointed knee of said toggle-joint being arranged to allow said hammer to rebound freely from said side wall after each stroke so as to enhance the resonance of the bell tone.

15. In an electric alarm clock: a cup-shaped bell comprising a bottom wall and a side wall; an electric motor mounted on said bottom wall within said side wall, said electric motor having a continuously-rotatable eccentric hammer-actuating pin within said bell; and mechanical alarm-means mounted on said bottom wall in juxtaposition to said motor, comprising a toggle-joint characterized by a loosely-jointed knee, a hammer formed integrally at one end of said toggle-joint and an actuating-member comprising an arm having an asymmetrical enlargement at one end, one edge of said enlargement being an extension

of one edge of said arm and a U-shaped notch intersecting the said one edge of said asymmetrical enlargement, said U-shaped notch exceeding in width the diameter of said eccentric-pin whereby said notch is arranged to operatively engage said eccentric-pin with a relatively-loose fit and a pivot-pin arranged to connect the opposite end of said actuating-arm to the opposite end of said toggle-joint thereby to transmit the movement of said actuating-arm to said hammer for impelling the latter against the side wall of said bell, the said loosely-jointed knee of said toggle-joint being arranged to allow said hammer to rebound freely from said side wall after each stroke so as to enhance the resonance of the bell tone.

16. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint characterized by a loosely-jointed knee, a hammer formed integrally at one end of said toggle-joint and an actuating-member having an enlargement at one end provided with a notch in one edge thereof arranged to operatively engage said eccentric-pin, said actuating-member being pivotally connected at its opposite end to the opposite end of said toggle-joint thereby to transmit the movement of said actuating-member to said hammer for impelling the latter against the side wall of said bell, the said loosely-jointed knee of said toggle-joint being arranged to allow said hammer to rebound freely from said side wall after each stroke so as to enhance the resonance of the bell tone; and an automatic alarm-release shaft arranged normally to project into said bell to engage said actuating-member and hold the notch thereof out of engagement with said eccentric-pin so as to disengage the latter from said toggle-joint, said alarm-release shaft being arranged to automatically disengage from said actuating-member to permit its notch to re-engage said eccentric-pin so as to re-engage the latter with said toggle-joint and transmit bell-striking motion to said hammer.

17. In an electric alarm clock: a cup-shaped bell comprising a bottom wall and a side wall; an electric motor mounted on said bottom wall within said side wall, said electric motor having a continuously-rotatable eccentric hammer-actuating pin within said bell; mechanical alarm-means mounted on said bottom wall in juxtaposition to said motor, comprising a toggle-joint characterized by a loosely-jointed knee, a hammer formed integrally at one end of said toggle-joint and an actuating-member having an enlargement at one end provided with a notch in one edge thereof arranged to operatively engage said eccentric-pin, said actuating-member being pivotally connected at its opposite end to the opposite end of said toggle-joint thereby to transmit the movement of said actuating-member to said hammer for impelling the latter against the side wall of said bell, the said loosely-jointed knee of said toggle-joint being arranged to allow said hammer to rebound freely from said side wall after each stroke so as to enhance the resonance of the bell tone; an automatic alarm-release control shaft arranged normally to project into said bell to engage said actuating-member and hold the notch thereof out of engagement with said eccentric-pin so as to disconnect the latter from said toggle-

joint, said alarm-release shaft being arranged to automatically disengage from said actuating-member to permit its notch to re-engage said eccentric-pin so as to connect the latter to said toggle-joint and transmit bell-striking motion to said hammer; and a manually-operated alarm-shutoff member mounted in said bell and arranged to engage said actuating-member to lift its notch from said eccentric-pin so as to discontinue the bell-striking operation of said hammer.

18. In an electric alarm clock: a cup-shaped bell comprising a bottom wall and a side wall; an electric motor mounted on said bottom wall within said side wall, said electric motor having a continuously-rotatable eccentric hammer-actuating pin within said bell; alarm mechanism mounted on said bottom wall in juxtaposition to said motor, comprising a toggle-joint characterized by a loosely-jointed knee, a hammer formed integrally at one end of said toggle-joint and an actuating-member having an enlargement at one end provided with a notch in one edge thereof arranged to operatively engage said eccentric-pin, said actuating-member being pivotally connected at its opposite end to the opposite end of said toggle-joint thereby to transmit the movement of said actuating-member to said hammer for impelling the latter against the side wall of said bell, the said loosely-jointed knee of said toggle-joint being arranged to allow said hammer to rebound freely from said side wall after each stroke so as to enhance the resonance of the bell tone; an automatic alarm-release shaft arranged normally to project into said bell to engage said actuating-member and hold the notch thereof out of engagement with said eccentric-pin so as to disengage the latter from said toggle-joint, said alarm-release shaft being arranged to automatically disengage from said actuating-member to permit its notch to re-engage said eccentric-pin so as to re-engage the latter with said toggle-joint and transmit bell-striking motion to said hammer; a manually-operated alarm-shutoff member mounted in said bell and arranged to engage said actuating-member to lift its notch from said eccentric-pin so as to discontinue the bell-striking operation of said hammer; and a guard carried by said alarm-shutoff member arranged to extend over said actuating-member in both its operative and inoperative positions to retain said actuating-member within the range of operation of said eccentric-pin.

19. An electric alarm clock comprising a dial; a dial back-plate; a time-train; a bell comprising a bottom wall and a side wall; means to support said bell on said dial back-plate in rearwardly-spaced relation thereto and with the side wall of said bell extending rearwardly of its bottom wall, said bottom wall and said dial back-plate constituting a movement-frame for supporting said time-train; an electric motor mounted on said bottom wall within said side wall and carrying a continuously-rotatable eccentric hammer-actuating pin, said motor also including a rotary-member extending through said bottom wall and operatively connected at its forward end with said time-train; and alarm mechanism mounted on said bottom wall within said side wall in juxtaposition to said motor, said alarm mechanism comprising a toggle-joint characterized by a loosely-jointed knee, a hammer formed integrally at one end of said toggle-joint and an actuating-member engaged at one end by said eccentric-pin and pivoted at its op-

posite end to the opposite end of said toggle-joint, thereby to transmit the movement of said actuating-member to said hammer for impelling the latter against the side wall of said bell.

- 5 20. An electric alarm clock comprising a dial; a dial back-plate; a time-train; a cup-shaped bell comprising a bottom wall and a side wall; means to support said bell on said dial back-plate in rearwardly-spaced relation thereto and with the side wall of said bell extending rearwardly of its bottom wall, said bottom wall and said dial back-plate constituting a movement-frame for supporting said time-train; an electric motor on said bottom wall within said side wall and carrying a continuously-rotatable eccentric hammer-actuating pin, said motor also including a rotary-member extending through said bottom wall and operatively connected at its forward end with said time-train; an alarm mechanism mounted on said bottom wall within said side wall in juxtaposition to said motor, said alarm mechanism comprising a toggle-joint characterized by a loosely-jointed knee, a hammer formed integrally at one end of said toggle-joint and a notched actuating-member engaged at one end by said eccentric-pin and pivoted at its opposite end to the opposite end of said toggle-joint, thereby to transmit the movement of said actuating-member to said hammer for impelling the latter against the side wall of said bell; and an automatic alarm-release shaft arranged normally to project rearwardly from said movement-frame into said bell to engage said actuating-member and hold the notch thereof out of engagement with said eccentric-pin so as to disconnect the latter from said toggle-joint, said alarm-release shaft being arranged to automatically disengage from said actuating-member to permit its notch to re-engage said eccentric-pin.
- 25 21. An electric alarm clock comprising a dial; a dial back-plate; a time-train; a cup-shaped bell comprising a bottom wall and a side wall; means to support said bell on said dial back-plate in rearwardly-spaced relation thereto and with the side wall of said bell extending rearwardly of its bottom wall, said bottom wall and said dial back-plate constituting a movement-frame for supporting said time-train; an electric motor mounted on said bottom wall within said side wall and carrying a continuously-rotatable hammer-actuating eccentric-pin at the rear thereof, said motor also including a rotary-member extending through said bottom wall and operatively connected at its forward end with said time-train; an alarm mechanism mounted on said bottom wall within said side wall in juxtaposition to said motor, said alarm mechanism comprising a toggle-joint characterized by a loosely-jointed knee, a hammer formed integrally at one end of said toggle-joint and an actuating-member engaged at one end by said eccentric-pin and pivoted at its opposite end to the opposite end of said toggle-joint, thereby to transmit the movement of said actuating-member to said hammer for impelling the latter against the side wall of said bell; and a manually-operative alarm-shutoff member supported without said side wall arranged to engage said actuating-member to lift its notch from said eccentric-pin so as to disengage the latter from said toggle-joint and discontinue the bell-striking operation of said hammer.
- 30 22. An electric alarm clock comprising a dial; a dial back-plate; a time-train; a cup-shaped

bell comprising a bottom wall and a side wall; means to support said bell on said dial back-plate in rearwardly-spaced relation thereto and with the side wall of said bell extending rearwardly of its bottom wall, said bottom wall and said dial back-plate constituting a movement-frame for supporting said time-train; an electric motor on said bottom wall within said side wall and carrying a continuously-rotatable eccentric hammer-actuating pin at the rear thereof, said motor also including a rotary-member extending through said bottom wall and operatively connected at its forward end with said time-train; an alarm mechanism mounted on said bottom wall within said side wall in juxtaposition to said motor, said alarm mechanism comprising a toggle-joint characterized by a loosely-jointed knee, a hammer formed integrally at one end of said toggle-joint and an actuating-member engaged at one end by said eccentric-pin and pivoted at its opposite end to the opposite end of said toggle-joint, thereby to transmit the movement of said actuating-member to said hammer for impelling the latter against the side wall of said bell; a manually-operative alarm-shutoff member sup-
